UNITED STATES PATENT OFFICE.

DAVID H. MILLER, OF CHICAGO, ILLINOIS, ASSIGNOR TO THE AMERICAN CHAINLESS WHEEL COMPANY, OF SAME PLACE.

VELOCIPED-E-GEAR.

SPECIFICATION forming part of Letters Patent No. 623,680, dated April 25, 1899.

Application filed December 15, 1897. Serial No. 661,967. (No model.)

To all whom it may concern:

Be it known that I, DAVID H. MILLER, a citizen of the United States of America, residing at Chicago, in the county of Cook and State 5 of Illinois, have invented certain new and useful Improvements in Velocipede-Gears, of which the following is a specification.

My invention relates to certain improvements in gears for velocipedes in which it is 10 desirable to mount the cranks upon or adjacent to the journals of the drive-wheel and at the same time gear up from the crank shaft or shafts to the drive-wheel to give the latter greater speed than the former.

15 The invention consists in certain devices relating to the mounting and gearing of the drive-wheel and cranks, which will be described in their preferred form and arrangement and the essential features of which will 20 be pointed out in the claim.

The drawings contain ten figures, of which Figure 1 is a side elevation of one of the many forms of velocipedes to which my invention may be applied. Fig. 2 is a vertical trans- 25 verse section in line 2 2 of Fig. 1. Fig. 3 is an enlarged side elevation of one of the crank-hangers. Fig. 4 is a horizontal section in line 4 4 of Fig. 1. Fig. 5 is a section in line 5 5 of Fig. 6 and shows the drive-wheel hub, axle, 30 and journals. Fig. 6 is a side elevation of the same. Fig. 7 is a view similar to Fig. 3, showing the opposite side of the hanger shown in the former figure. Fig. 8 is a vertical section in line 8 8 of Fig. 2. Fig. 9 is a 35 detail side elevation showing the connection of a portion of the frame with the crank-hangers, and Fig. 10 is an end elevation of the same.

Referring to the drawings, A A' are two 40 hanger-plates rigidly supported by the frame of the machine and each containing a preferably central opening a and a slot a' , the opening being shown as screw-threaded and the walls of the slot as containing a V-shaped groove. A bearing-collar B is externally threaded to fit the opening a and is secured in said opening and held therein against rotation by a jam-nut b . An internal gear C is secured upon the crank-shaft D, (here shown 45 as threaded thereto,) and is locked by means of a jam-nut d . A covering E, having a cen-

tral perforation adapted to receive the crank-shaft, is placed upon said crank-shaft before the internal gear is secured thereon. The crank-shaft is then inserted in the bearing- 55 collar B. Said bearing-collar has formed in it bearing-cups $b' b'$. The nut d has a cone d' corresponding to one of the cups. A nut d^2 , threaded upon the inner end of the crank-shaft, has a cone corresponding to the other 60 of the cups, and said nut d^2 is locked in proper adjustment by means of a jam-nut d^3 .

In the slot a' , having the grooved walls, is placed a slide F, which is shown in side elevation in Fig. 6 and in its proper place in 65 the hanger-plate in Fig. 3. The edges of the slide are fitted to the grooved walls of the slot, and upon the inner surface of said slide is a lug f , extending laterally beyond the slot and secured to a pair of lugs $a^2 a^3$ (see Fig. 70 7) upon the inner side of the hanger-plate by means of the screws G G'. (Shown in Fig. 3 in dotted lines.) The upper end of each of the slides F has an inwardly-extending boss f' , shown by the two intersecting sections seen 75 in Figs. 2 and 5, and in this boss is formed a bearing containing two ball cups or races f^2 . The axle h of the drive-wheel H bears a cone h' , corresponding to one of the cups f^2 , and said axle extends through the boss f' and has 80 threaded upon it a pinion h^2 in mesh with the internal gear C and bearing a cone corresponding to the other of the two cups f^2 . Suitable balls are provided in the bearing, and the pinion h^2 is secured against rotation on 85 the axle h by means of a jam-nut h^3 . The boss f' also serves as a pivot to hold the rear extremity of two braces O P, extending back from the front portion of the frame, said braces terminating in a common block o, having 90 a removable end piece or yoke o' .

The frame shown in the drawings is so constructed that certain members of the same have a limited oscillating movement with respect to the other members, this being accomplished by pivoting certain members of the framework together, as is clearly illustrated in Fig. 1, and specifically described in my pending application for United States patent for improvements in bicycle-frames filed December 15, 1897, and given Serial No. 661,966. 95 100

The specific form and arrangement of the

various devices are not essential to the invention, broadly considered, inasmuch as more or less variation is possible without departing materially from said invention.

5 I claim as new and desire to secure by Letters Patent—

In a geared crank-shaft hanger, the combination with a slotted and perforated hanger-plate, of a slide containing a drive-wheel bearing and fitted to said slot, a drive-wheel fast upon its axle and having an axle extending through said bearing, a gear secured to said axle upon the opposite side of the bearing, a bearing-collar secured in the perforation, a 10 crank-shaft therein provided with a crank, an internal gear mounted upon the crank-shaft and in mesh with the drive-wheel gear,

a cover secured to the hanger-plate and inclosing both of said gears, suitable ball-races in the bearing-collar, a cone threaded upon 20 the shaft and holding the internal gear in place thereon, a second cone adjustably clamped upon the opposite end of the shaft and suitable balls adapted to said races and said cones; substantially as described.

25 In witness whereof I have hereunto set my hand, at Chicago, in the county of Cook and State of Illinois, this 7th day of December, A. D. 1897.

DAVID H. MILLER.
